UNITED STATES PATENT OFFICE.

CHARLES H. HOPP, OF CHICAGO, ILLINOIS.

BOBBIN-WINDER FOR SEWING-MACHINES.

SPECIFICATION forming part of Letters Patent No. 268,896, dated December 12, 1882.

Application filed September 16, 1882. (No model.)

To all whom it may concern:

Be it known that I, CHARLES H. HOPP, of Chicago, county of Cook, State of Illinois, have invented a new and useful Improved Automatic Bobbin-Winder, which is fully set forth in the following specification and accompanying drawings, in which—

Figure 1 is a side view of my improved automatic bobbin-winder; Fig. 2, a cut section of the same; Fig. 3, a top view thereof; Fig. 4, a side view thereof when out of contact with the band-wheel; Fig. 5, an end view thereof. Fig. 6 represents the latch-lever and bobbin, and Fig. 7 the worm-wheel and different positions assumed by the worm in connection therewith.

The object of my invention is to provide a bobbin-winding mechanism for use with sewing-machines which shall be self-acting in its provisions of tension to secure the even winding of the thread in the bobbin and stoppage of winding when the bobbin is full, with a cutting device, to sever the thread, upon the latch-lever which throws the bobbin-winding mechanism out of gear.

A represents the base as secured to a sewing-machine table by screws *a a*; B, the movable frame thereof supporting the bobbin, worm-shaft, tension-spring, and latch-lever; C, the bobbin; D, the worm and its shaft; E, the worm-wheel; F, the latch-lever; G, its spring; H, the thread-check; I, the frame-stud; J, the frame-spring; K, the adjusting-spring; L, the bobbin-spindle; M, the rubber-wheel; O, the latch-lever screw; P, the shoulder on base A; R, the band-wheel of a sewing-machine.

The operation of these parts is as follows: Base A being secured to the table of a sewing-machine by screws *a a*, rubber wheel M is brought into contact with band-wheel R, and the short arm of latch-lever F catches upon shoulder P of base A. The revolution of band-wheel R rotates rubber wheel M, connected with shaft and worm D, engaging with worm-

wheel E upon bobbin-spindle L. The long arm of latch-lever F lies within the disks of bobbin C, held there by spring G. As the thread coming through thread-check H is wound upon bobbin C, it gradually fills the space between the disks until its body presses out the longer arm of latch-lever F, thereby releasing the shorter arm from shoulder P, and frame-spring J raises the forward end of frame B, thereby destroying the contact between rubber wheel M and band wheel R.

The lower edge of the long arm of latch-lever F is a cutting-edge, and the operator may now sever the thread by drawing it across the same.

Thread-check H is provided with a disk and spring, common to sewing-machines, whereby sufficient tension is obtained upon the thread to secure its even and regular winding upon the bobbin.

To secure elasticity in the action of wheels R and M, tending by their rigidity to cut rubber wheel M or break latch F, that part of frame B which supports rubber wheel M and worm-shaft D is allowed to rock slightly upon frame-stud I, being held in position by adjusting-spring K, which allows worm D to rise and fall slightly (see Fig. 7) in its engagement with worm-wheel E, and thereby compensatingly relieve the pressure upon rubber wheel M.

What I claim as my invention, and desire to secure by Letters Patent, is—

The combination of base A, provided with shoulder P, frame B, having the rubber wheel and worm-supporting part thereof adapted to rock slightly, bobbin C, latch-lever F, and thread-check H, with worm D and worm-wheel E, operating together by means of the springs and connections shown, substantially as and for the purpose described.

CHARLES H. HOPP.
